DOUBLE-ACTING INTERNAL-COMBUSTION ENGINE

Application filed July 20, 1928, Serial No. 294,200, and in Switzerland November 13, 1927.

This invention relates to double-acting internal combustion engines of the kind in which the cylinder is provided with a jacket containing a removable inner cylindrical member or barrel forming or carrying a liner for the piston, and has for its object to provide a cylinder of relatively light construction while capable of withstanding considerable internal pressures.

According to this invention the cylinder jacket is provided with a removable inner cylindrical member or barrel the end of which nearest the crankshaft is of reduced diameter or partially closed so as to form a neck, and a detachable annular member or plug is provided adapted to cooperate with or engage the neck in such a manner that the barrel and the plug together form a complete unit to accommodate the piston and piston rod. Either the barrel or the plug or both these parts are supported by or connected to the jacket, the arrangement being such that relatively light bolts or studs can be employed since some of the pressures which are developed within the cylinder are transmitted to the jacket through the shoulders or partially closed end of the barrel leaving only the remaining pressures to be dealt with by the removable annular plug. The plug is furnished with a stuffing box or other packing means for the piston rod and in one construction the plug forms the means of connection between the barrel and the jacket.

Preferably the shoulders of the barrel, i. e. the partially closed end surrounding the neck, are formed rounded and are provided with one or more openings to receive the valves or parts of the valves controlling the working chamber adjacent to the crank. The plug may be connected in the cylinder jacket by means of a bayonet joint so that it can be readily withdrawn or any other known means may be employed.

Three constructions according to this invention are illustrated somewhat diagrammatically by way of example in the accompanying drawings, in which

Figure 1 is a vertical cross-section showing the lower portion of the cylinder of a

double-acting internal combustion engine, and

Figures 2 and 3 are similar views of modified constructions.

Figure 4 is a vertical cross-section diagrammatically illustrating a complete double-acting engine in accordance with the invention.

Fig. 5 is a detailed section on line 5—5 of Fig. 3.

In the construction illustrated in Figure 1, the piston rod 1 carries a piston 2 adapted to reciprocate in a removable barrel 3 which may also constitute a liner, the lower end of the barrel being furnished with a flange adapted to engage an internal shoulder 4 on the cylinder jacket. The lower end of the barrel is partially closed or of reduced diameter so as to form a neck 10 adapted to receive a removable annular plug 5 furnished with a central aperture 6 to receive a stuffing box having a gland 7.

The plug 5 contains a hollow chamber 8 to contain a cooling medium and is secured to the barrel by bolts 15, the diameter of the plug being so small that it has only to withstand a relatively small part of the working pressures so that the bolts 15 may be of light construction. The space between the outer wall of the barrel 3 and the inner wall of the jacket constitutes a cooling chamber 9. It will be seen that the removable barrel and the plug 5 together form a complete unit to accommodate the piston and its rod.

The shoulder of the barrel, i. e. partially closed end surrounding the neck, is preferably rounded as shown giving a cup-like shape to the lower combustion chamber and thus avoiding projecting corners which reduces heat losses. A portion of the pressure of the working fluid is transmitted to the cylinder jacket through the shoulder of the barrel without necessitating the use of bolts for dealing with this portion of the pressure.

In the construction illustrated in Figure 1, after the piston has been removed through the cylinder, the lower half of the cylinder may be detached and withdrawn upwards as a single unit or the barrel, the jacket and the plug may be individually withdrawn.

If the jacket and the plug are of the relative dimensions shown by the dotted lines 13 and 14 in Figure 1, the plug and barrel can be withdrawn as a unit without disturbing the jacket.

5 In the modified construction shown in Figure 2, the plug 5 directly bears against a shoulder on the jacket 4 whilst the barrel bears against a shoulder on the plug. Thus the plug serves to connect the jacket to the barrel.

In Figure 3 a further modification is illustrated in which there is a bayonet joint between the removable plug and the cylinder jacket, an annular plate 16 furnished with the necessary slots being connected to the cylinder jacket by screwthreaded members 17. At its upper end the plug is provided with a flange or shoulder to engage a corresponding shoulder in the neck portion of the barrel so that the bayonet joint serves to retain in position not only the plug but also the barrel. When the plug is to be removed the screws 17 are slackened off and the annular plate turned and allowed to fall whereupon the plug alone or together with the barrel may be withdrawn upwards through the cylinder. The view of the bayonet plug shown in Fig. 5 is that as it appears when tightened or released. The cheeks 21 are associated with the cylinder cover plug 5, but the cheeks 20 contact with the bayonet plug plate 16. If the cylinder cover is to be tightened, the bayonet plug plate 16 is pushed from the bottom to the top axially in the position shown in Fig. 5 until it has reached the level represented in Fig. 3, whereafter the bayonet plug plate is rotated by 60° in a manner such that the axis A (Fig. 5) moves into the position B. As a result, the cheek 20 of the bayonet plug 16 is pushed over the cheek 21 of the cylinder covers. In this position, the screws 17 are tightened so that the whole system is united rigidly. In releasing the bayonet plug 16, the reverse process is employed. First, the screws 17 are released, then the axis A of the bayonet plug, which is in the position B, is rotated back again by 60° so that the bayonet plug will occupy the position represented in Fig. 5, after which movement the bayonet plug directly drops out toward the bottom.

It becomes evident from Fig. 4 that on general principles the subject matter of the invention can be used just as well for the upper as for the lower half of the cylinder. If as according to Fig. 3, the cylinder head is also used for the upper half of the cylinder, the place of the piston rod 1 and the associated stuffing box 6, 7 will be occupied by a filler which contains the fuel valves and the remaining members required for running the engine.

It will be appreciated that the invention is equally applicable to engines having hori-

zontal or inclined cylinders and that the particular construction of the barrel and liner will vary in accordance with the nature and dimensions of the internal combustion engine.

I claim:

1. In a double-acting internal combustion engine, the combination with a cylinder jacket of a removable cylinder liner having its end nearest the crank-shaft reduced to form a neck, and a detachable plug extending into said neck and forming with said liner a complete unit supported by said jacket.

2. In a double-acting internal combustion engine, the combination with a cylinder jacket of a removable cylinder liner having its end nearest the crank-shaft reduced to form a neck, and a detachable plug shouldered on said jacket and telescoping into said neck, said plug forming with said liner a complete unit supported by said jacket.

3. In a double-acting internal combustion engine, the combination with a cylinder jacket of a removable cylinder liner having its end nearest the crankshaft rounded and reduced to form a neck, and a detachable plug extending into said neck and closing the rounded end of said liner, said plug forming with said liner a complete unit supported by said jacket.

4. In a double-acting internal combustion engine, the combination with a cylinder jacket of a removable cylinder liner, having its end nearest the crank shaft reduced to form a neck, a detachable plug extending into said neck, said plug having a rounded end closing said neck, and means for supporting said plug and liner on said jacket.

5. In a double-acting internal combustion engine, the combination with a cylinder jacket of a removable cylinder liner having its end nearest the crank shaft reduced to form a neck, a detachable plug extending into said neck and forming a complete unit with said liner, and a detachable locking plate engaging said plug and said jacket and locking said plug and liner to said jacket.

6. In a double-acting internal combustion engine, the combination with a cylinder jacket of a removable cylinder liner having its end nearest the crank reduced to form a neck, a detachable plug adapted to engage said neck and form a complete unit with said liner, said plug having bayonet joint lugs thereon, and an annular plate adapted to cooperate with said lugs and releasably lock said plug to said jacket.

In testimony whereof I have affixed my signature.

GEORGE FERGUSON.
